UNITED STATES PATENT OFFICE.

CHARLES S. JACKSON, OF FRANKLIN, OHIO.

PAPER-BAG MACHINE.

SPECIFICATION forming part of Letters Patent No. 722,986, dated March 17, 1903.

Application filed August 6, 1902. Serial No. 118,610. (No model.)

To all whom it may concern:

Be it known that I, CHARLES S. JACKSON, a citizen of the United States, residing at Franklin, in the county of Warren and State of Ohio, have invented certain new and useful Improvements in Paper-Bag Machines, of which the following is a specification.

The object of my invention is to provide a paper-bag machine which will automatically insert a strawboard plate in the bottom of the bag during the process of manufacture; and my invention consists in the combination and arrangement of parts hereinafter described and claimed.

15 In the drawings, Figure 1 is an elevation of an apparatus for inserting a strawboard plate in the bottom of a bag, together with a diagrammatic representation of so much of a paper-bag machine as coöperates with the apparatus; Fig. 2, an elevation of the clutch mechanism for operating the apparatus; Fig. 3, a section on line 3 3 of Fig. 2; Fig. 4, a top plan view of the apparatus; Fig. 5, an end view of the apparatus; Fig. 6, an elevation showing 20 the means by which the apparatus is driven; Fig. 7, a top plan view showing the bag as it appears in the process of manufacture just before the strawboard plate is applied; Fig. 8, a top plan view of the bag and strawboard 25 plate after the plate has been applied and the first fold made, and Fig. 9 a top plan view showing the completed bag.

Reference-letter A denotes the strawboard plate; B, a rack for containing the plates; C, a feed-slide for delivering the plates; D, a rack-bar for operating slide C; E, a gear meshing with rack-bar D; E', a shaft carrying gear D; F, a sprocket-wheel for operating shaft E; G, a chain operating sprocket-wheel F; H, a sprocket-wheel operating chain G; I, a rod; J, a crank for operating sprocket-wheel H; K, the bags; L, the nose of the paper-bag machine; M and N, tucker-blades for starting the folds in the bag, and O and P folding- 30 rolls of the bag-machine.

45 The plates A are placed in a pile in rack B, which is adjustable both lengthwise and crosswise for the accommodation of different-sized plates. An adjustable gate b is provided to 50 permit the passage of the bottom plate and prevent the passage of the others. The sides b' of rack B are extended to form a channel for

the plates A, and at its forward end the rack is provided with an adjustable table b², having a folding extension b³. The slide C operates in guides c in the bottom of the rack and is provided with stops c' and c² for carrying the plates. The rack-bar D is carried by slide C and meshes with gear E, carried by shaft E'. As a means for operating shaft E', I provide a 55 sprocket-wheel F, loosely mounted on shaft E' and carrying a clutch member e, engaging a corresponding clutch member e', fixed to shaft E'. A spring e² holds clutch members e and e' in engagement. A space e³ is left 60 between the engaging surfaces of clutch members e and e', so that there will be a little lost motion at each reversal of shaft E'. In order to obviate danger of breakage by accident, the engaging surfaces of clutch members e and e' are beveled, so that they will 65 disengage should too great resistance be placed upon them. The sprocket-wheel F is driven by sprocket-chain G, passing over sprocket H, which is operated through rod I 70 by crank-arm J on shaft j. Shaft j is driven by some suitable power, so as to coöperate with the other operations of the bag-machine, and may, if desired, be one of the regular 75 shafts of the bag-machine extended for this purpose. The length of crank-arm J is such that it does not cause a complete rotation of sprocket-wheel H, but merely a rocking motion. Thus it will be seen that the crank-arm J will impart a reciprocating movement 80 to slide C, having a momentary pause at each reversal due to the lost motion between clutch members e and e'. In order to adjust the movement of slide C, a turnbuckle i may be provided on rod I. At each forward movement of slide C stop c' engages the bottom plate A, carrying it under gate b and past dogs b⁴, which falling behind it prevent its return. On the backward movement of slide 85 C stop c² passes under plate A and engages 90 it upon the next forward movement to carry it forward onto table b², where owing to the pause of slide C at the reversal it is momentarily held against nose L of the bag-machine. While the plate is in this position the usual 95 tucker-blade M descends and, striking the edge of plate A projecting over table b², tips the plate, so that stops m on the blade engage it and carry it down with the blade. In 100

order to accommodate different sizes of plates, the stops m may be made adjustable. The extension b^3 is pivoted to table b^2 and has a rod connection with arm m' on tucker-blade shaft m^2 , so that as the blade descends the extension is automatically withdrawn and replaced when the blade ascends. The usual operations of the bag-machine bring the bag K in the condition represented by Fig. 7, with paste applied along lines $k\ k$ under nose L, and table b^2 in proper position to be engaged by the descending tucker-blade M along line $k'\ k'$, so as to start a fold on this line. As the bag approaches this position its end has a tendency to curl up, and extension b^3 prevents this. The tucker-blade M carries the fold in bag K and the inclosed plate A down into engagement with rolls O, which draw the bag through them, fold first. The rolls O apply the paste-supplied portions of the bottom of bag K to opposite sides of plate A, where they are held by the paste. After this operation the bag is in the condition represented by Fig. 8. As the bag continues its course it is struck by tucker-blade N along line $k^2\ k^2$ and carried through rolls P, completing the bag with the plate A in its bottom. The plate A is preferably of strawboard or other more or less porous material, which will absorb superfluous moisture and prevent the paste from becoming moldy or mildewed.

The tucker-blades M and N and rolls O and P are the usual parts of the well-known paper-bag machine for forming and pasting the folds in the bottom of the bag, and their operation for this purpose will be readily understood by those skilled in the art without further description. My invention consists in providing the means to coöperate with these parts, whereby the strawboard plates are automatically inserted in the bottom.

While I have shown and described the preferred form of application of my invention, this is obviously capable of many variations without departing from the spirit of the invention. I therefore do not wish to be limited to the exact form shown and described; but

50. What I claim as my invention is—

1. The combination, with the tucker-blade and folding-rolls of a bag-machine, of means for placing a plate in the path of the tucker-blade, to be engaged thereby and carried to the rolls in the fold caused by the blade, substantially as specified.

2. The combination, with the tucker-blade and folding-rolls of a bag-machine, of a table located near the path of the tucker-blade; means for placing a plate on the table with its edge projecting into the path of the tucker-blade; and means for carrying the plate inclosed in the fold into the folding-rolls, substantially as specified.

65. 3. The combination, with the tucker-blade and folding-rolls of a bag-machine, of a table

located near the path of the tucker-blade; means for placing a plate on the table with its edge projecting into the path of the tucker-blade; and a stop on the tucker-blade, adapted to engage the upturned edge of the plate and carry it to the folding-rolls, substantially as specified. 70

4. The combination in a bag-machine of a tucker-blade; folding-rolls adapted to coöperate with the tucker-blade to fold the bag; means for placing a plate in the path of the tucker-blade to be engaged thereby and carried to the rolls in the fold caused by the blade; and a second tucker-blade and pair of folding-rolls to complete the folding of the bottom of the bag, substantially as specified. 75

5. In an apparatus for feeding plates to a bag-machine, the combination of a rack adapted to contain a pile of plates; a gate adapted to permit the passage of the bottom plate from the pile and to prevent the passage of the others; a slide adapted to engage the bottom plate of the pile and carry it to a bag-machine; and means for incorporating the plate 80 in the bottom of the bag, substantially as specified. 85

6. In an apparatus for feeding plates to a bag-machine, the combination of a rack adapted to contain a pile of plates; a gate adapted to permit the passage of the bottom plate from the pile and to prevent the passage of the others; a slide mounted to reciprocate under the rack; a stop on the slide, adapted to engage the bottom plate and carry it toward a 90 bag-machine; a dog adapted to engage the plate and prevent its return; and a second stop on the slide adapted to engage the plate and deliver it to the bag-machine, substantially as specified. 95

7. In an apparatus for feeding plates to a bag-machine, the combination of rack B, provided with gate b and table b^2 ; slide C, having stops c' and c^2 ; dogs b^4 ; rack-bar D on slide C; gear E; shaft E'; sprocket F; chain G; sprocket H; rod I; and crank J, substantially as specified. 105

8. In an apparatus for feeding plates to a bag-machine, the combination of rack B, provided with gate b and table b^2 ; slide C, having stops c' and c^2 ; dogs b^4 ; rack-bar D on slide C; gear E; shaft E'; sprocket F; clutch members e and e'; spring e'; chain G; sprocket H; rod I; and crank J, substantially as specified. 115

9. The combination, with the tucker-blade and folding-rolls of a bag-machine, of a table located near the path of the tucker-blade; a rack adapted to contain a pile of plates; a gate adapted to permit the passage of the bottom plate of the pile and prevent the passage of the others; and a slide adapted to engage the bottom plate of the pile and place it on the table with its end projecting into the path of the tucker-blade, substantially as specified. 125

10. The combination, with the tucker-blade and folding-rolls of a bag-machine, of a table

located near the path of the tucker-blade; a rack adapted to contain a pile of plates; a gate adapted to permit the passage of the bottom plate of the pile and prevent the passage 5 of the others; a slide adapted to engage the bottom plate of the pile and place it on the table with its end projecting into the path of the tucker-blade; and a stop on the tucker-blade adapted to engage the plate and carry 10 it with the blade, substantially as specified.

11. The combination in a bag-machine of rack B, provided with gate b and table b²; slide C, having stops c' and c²; dogs b⁴; rack-bar D on slide C; gear E; shaft E'; sprocket-wheel F; chain G; sprocket-wheel H; rod I; 15 wheel F; chain G; sprocket-wheel H; rod I;

crank J; tucker-blade M, having stop m; and rolls O, substantially as specified.

12. The combination in a bag-machine of rack B, provided with gate b and table b²; slide C, having stops c' and c²; dogs b⁴; rack-bar D on slide C; gear E; shaft E'; sprocket-wheel F; chain G; sprocket-wheel H; rod I; 20 crank J; tucker-blade M, having stop m; rolls O; tucker-blade N; and rolls P; substantially as specified.
